John G. Day of Brooklyn - New York

Letters Patent

The Schedule referred to in these Letters Patent and making part of the same containing a description in the words of the said John G. Day himself of his improvement in the construction of Abutting Piers of Bridges and Dredge water or artificial Harbors.

To all to whom these presents shall come. Whereas it appears that John G. Day of the City of Brooklyn in the County of Kings and State of New York has invented a new and useful improvement in the building and constructing of abutting Piers, Piers of Bridges and Dredge water or artificial Harbors. and the following is a full and exact description of the said improvement. In the construction of either of the above works (which may be of stone or cast iron) it is intended to put the blocks of stone or cast iron in their places by means of conductors secured in the foundations which is to be laid and put in place by means of the diving Bell. When the foundation is laid down is done with the greatest care. Heavy pieces or pillars of any stone or iron may be raised theron by the following process: if a Harbor is intended take square Blocks of stone or many other hard stone or iron of cast iron say eight or ten feet long and one or two feet square. Prepare two of them with a conductor to each end of iron or copper wire from one to two inches in diameter (or larger if found necessary) and to be so placed that when the stone or iron is secured in the bottom the said conductor will reach above the surface of the water. When that is done prepare for more stone or blocks of cast iron of the same size having holes through them so that they can be secured on the aforesaid conductors and passing down the stone let them be placed transversely across the first. The ends of each block having been previously so cut or prepared that they may come together with a close joint. In the same way continue to place each block, passing down on

condustry by means of holes through said blocks transversely across each porous layer until the water is raised above the surface of the water. In each succeeding row of blocks be so much shorter than the last that when the pier is raised to the surface of the water there may be a difference of four feet between the base and the top but this difference must be all on the outer side. For a pier of twenty five or thirty feet wide three of these pillars will be necessary. They may be placed ten feet from the abutment in a line and every twenty feet in length of which in line of these piers or pillars will be required. and if four feet base they will be placed ten feet apart. When the said piers or pillars are raised a little above the surface of the water anchorage to be turned from one line of piers or pillars to the other, and over the top of these anchors after securing the work may be laid heavy planking. Some of the stones need to be cut enough for the abutments above described and also for the facing or finishing the upper part of the way. Uprights are placed eight or ten feet apart up and down the sides of the cliff, to keep rocks from falling against the stone work, and instead of descending they must be decked. This of Rock are intended to be built in the manner as one of the piers above described with this addition they must be larger at the base and become more and more solid. The rock walls or artificial harbors are on the same principles with this difference. That instead of piers of dry stone there will be a wall of piers twenty feet to fifty feet and one hundred feet in thickness. This must be done in a concentric manner and commences on shore and raised off into the Bay or water in the direction which may be convenient and be constructed in the manner above mentioned.

On testimony that the above is a true specification of my said improvement as above described. I doo declare before my honor the fourteenth day of September in the year of our Lord one thousand eight hundred and thirty four
